COMBINED SHIPPER AND GEAR CASING LOCK

Application filed October 24, 1928. Serial No. 314,758.

The invention is designed mainly for cotton mill machinery and particularly for roving frames to insure safety and guard against accidents when machinery is running.

The invention relates to machinery and including enclosed gearing and a shipper rod for starting and stopping the machinery. The invention contemplates a latch member mounted upon the shipper rod to move therewith and engageable with a fixed part to secure the shipper rod against movement when occupying a position with the machinery at rest and out of action.

The invention furthermore provides fastening means for the closure, which controls access to the box, housing or casing containing the gearing, to prevent opening thereof when the machinery is running, said fastening means being mounted upon the frame, or like supporting part, and connected with the shipper rod to be actuated thereby to release the closure when the machinery is at rest and to secure the closure when the machinery is in motion according to the position of the shipper rod.

While the drawings illustrate a preferred embodiment of the invention, it is to be understood that in adapting the means to meet specific needs and requirements, the design may be varied and such other changes in the minor details of construction may be resorted to within the scope of the invention, as claimed, without departing from the spirit thereof.

For a full understanding of the invention and the merits thereof, reference is to be had to the following description and the drawings hereto attached, in which:

Figure 1 is a side view of safety means embodying the invention, showing the same applied to a roving frame, the full lines showing the shipper rod locked and the closure to the gear casing released and the dotted lines showing the closure to the gear casing locked and the shipper rod moved to throw the machinery in action.

Figure 2 is a detail sectional view on the line 2—2 of Figure 1 looking to the right as designated by the arrows.

Figure 3 is a detail sectional view on the line 3—3 of Figure 1 looking to the left as indicated by the arrows.

Figure 4 is a detail perspective view of the fastening means for the closure to the gear casing.

Corresponding and like parts are referred to in the following description and designated in the several views of the drawings by like reference characters.

The numeral 1 denotes a roving frame and 2 the closure to the gear casing or box which contains the twist and builder motion gearing. The numeral 3 designates the usual shipper rod for throwing the operating mechanism into and out of gear.

The numerals 4 and 5 designate fixed bearings in which the shipper rod 3 is mounted. These parts are of well known construction and arrangement, and are illustrated to demonstrate the application of the invention, and are representative of equivalent parts in other machinery including a shipper member and a closure requiring to be made secure when the machine is in action.

The safety means includes a pivoted latch member embodying an arm 6 and a nose 7 at the swinging end of the arm 6 and adapted to engage the bearing 4 and secure the shipper rod 3 against movement when the frame is out of action or not running. The nose 7 is depressed to embrace the upper portion of the rod 3 and prevent lateral displacement of the free end of the arm 6 when the latter is in operative position. The latch member is pivoted to a post 8 which is mounted upon the shipper rod 3 and secured thereto so as to move therewith.

A clamp screw 9 threaded into the post 8 bindingly engages the rod 3 at its inner end to secure the post to the rod in the required adjusted position. When the shipper rod 3 is moved to the left to the limit of its throw, the machinery of the roving frame is thrown out of action, and this brings the safety means into position so that when the latch member is thrown forwardly and downwardly its nose 7 engages the rod 3 in front of the bearings 4, with the result that

the shipper rod is prevented from being accidentally moved towards the right to throw the machinery in gear, thereby avoiding an accident should one be oiling or adjusting the gearing located within the box or casing 1.

The fastening means for the closure 2 is pivotally mounted upon the frame 1 and is adapted to be automatically operated by the shipper rod 3. The numeral 10 denotes a plate, which is bolted or otherwise secured to the frame 1 and formed with a sleeve 11, in which is mounted a journal 12 formed at one end of an arm 13. A longitudinal slot 14 is provided in the end portion of the arm 13 and receives a screw 15 or like part applied to the post 8. Longitudinal movement of the shipper rod 3 effects a pivotal movement of the arm 13, the journal 12 of which rotates in the sleeve or bearing 11. An extension 16 projects laterally from the outer end of the journal 12 in an opposite direction to the arm 13. A member 17 projects laterally from the extension 16 and terminates in an offset portion 18 which is adapted to project across the part of the closure 2 and prevent its opening when the frame or machinery is running, as indicated most clearly by the dotted lines in Figure 1 of the drawings. When the shipper rod 3 is thrown to the right the fastening means is simultaneously operated to prevent opening of the closure 2. When the shipper rod 3 is moved to the left to throw the machinery out of action the fastening means is simultaneously actuated to release the closure 2 and admit of access to the gear casing or box 1, for any desired purpose, and to prevent accidental movement of the shipper rod it is held by operating the latch member to cause the hose 7 thereof to engage the bearing 4, as indicated most clearly in Figure 1 of the drawings.

Having thus described the invention, we claim:

1. The combination with a shipper rod and a bearing therefor, of a post adapted to be secured to the shipper rod in an adjusted position, and a latch member pivoted to the post and including a nose to engage the said bearing and rest upon the shipper rod and prevent movement thereof in one direction.

2. The combination with a gear box closure, a shipper rod and a bearing therefor, of a post adjustably secured to the shipper rod, a latch member pivoted to the post and adapted to engage the said bearing of the shipper rod, and fastening means pivotally mounted intermediate its ends, and having one end adapted to secure the said gear box closure, and having the opposite end slidably connected with the said post.

3. In combination with the closure of a machine casing and shipper rod for throw-

ing the machine into and out of operation, of an arm pivoted on the frame of the machine having a terminal adapted to extend over and prevent opening of the closure when the arm is at one limit of its pivotal movement, there being a slot in the other end of said arm, a post on said shipper rod having a pin engaging in said slot for rocking said arm, a latch pivoted on said post, and a bearing on said machine frame for the shipper rod forming a stop for engaging the latch and preventing accidental movement of the shipper rod to operate the machine when said arm is disengaged from said closure.

In testimony whereof we affix our signatures.
